(57) **CLAIM**

The ornamental design for an adhesive support for lymphatic flow, as shown and described.

DESCRIPTION

FIG. 1 is a top view of an adhesive support for lymphatic flow showing our new design.

FIG. 2 is a first perspective view of the adhesive support for lymphatic flow; and,

FIG. 3 is a second perspective view of the adhesive support for lymphatic flow.

It is understood that the adhesive support for lymphatic flow shows no appreciable thickness.

The broken lines shown in the drawings illustrate environmental structure and form no part of the claimed design.
